BOAT LIGHT HOUSING OR SIMILAR ARTICLE

Robert M. Selzer, Los Angeles, Calif.

Application December 26, 1958, Serial No. 53,907

Term of patent 14 years

(Cl. D48—32)

Fig. 1 is a side elevational view of a boat light housing or similar article embodying my new design;

Fig. 2 is a front elevational view thereof;

Fig. 3 is a top view thereof with the upper lens member omitted for convenience of illustration; and

Fig. 4 is a perspective view thereof, as viewed from the top of Fig. 1.

The lenses are shown in broken lines for illustrative purposes only.

I claim:

The ornamental design for a boat light housing or similar article, substantially as shown and described.
